Primary Examiner — David Muller*Assistant Examiner* — Nathan Johnston(74) *Attorney, Agent, or Firm* — Pearne & Gordon LLP(57) **CLAIM**

The ornamental design for a hot and cold pack mask, as shown and described.

DESCRIPTION

FIG. 1 is a front my new hot and cold pack mask, shown disassembled into its two constituent portions;

FIG. 2 is a right side view thereof;

FIG. 3 is a top view thereof;

FIG. 4 is a left side view thereof;

FIG. 5 is a bottom view thereof;

FIG. 6 is a rear view thereof;

FIG. 7 is a front sectional view thereof, taken along section lines 7-7;

FIG. 8 is a rear sectional view thereof, taken along section lines 8-8; and,

FIG. 9 is a perspective of my new hot and cold pack mask, shown fully assembled and worn on the head of a person. The broken lines located in FIGS. 1 and 6-9 are identified as stitching that forms part of the claimed design.

All other features shown in broken lines depict environmental subject matter only and form no part of the claimed design.
